[57] CLAIM

The ornamental design for holder for advertising display or the like, as shown and described.

DESCRIPTION

FIG. 1 is a front elevational view of a holder for advertising display or the like, showing my new design;

FIG. 2 is a rear elevational view thereof;

FIG. 3 is a top plan view thereof;

FIG. 4 is a bottom plan view thereof;

FIG. 5 is a right side elevational view thereof, with the left side being a mirror image;

FIG. 6 is a front elevational view on a reduced scale shown in an environmental form thereof, with the broken lines shown for illustrative purposes only and forming no part of the claimed design.

FIG. 3

FIG. 6
